REVERSING-GEAR FOR INTERNAL-COMBUSTION MOTORS.

1,019,947.

Specification of Letters Patent. Patented Mar. 12, 1912.

Application filed April 13, 1910. Serial No. 555,236.

To all whom it may concern:

Be it known that I, GUSTAVE CARELS, a subject of the Kingdom of Belgium, residing in Ghent, Kingdom of Belgium, have 5 invented certain new and useful Improvements in Reversing-Gear for Internal-Combustion Motors; and I do hereby declare the following to be a full, clear, and exact description of the invention, such as will enable others skilled in the art to which it 10 pertains to make and use the same, reference being had to the accompanying drawings, and to letters or figures of reference marked thereon, which form a part of this specification.

15 This invention has for its object to provide an improved reversing gear for internal combustion motors whereby the motor can be reversed by carrying out in succession the following operations, namely: (1) stopping the admission of the combustible mixture; (2) shifting the valves into the positions for producing the reverse motion of the motor; (3) admitting compressed air 20 for producing first a braking action and then the reverse motion of the motor; and (4) readmitting the combustible mixture.

It has already been proposed to carry out the above stated operations by the following 25 characteristic means:—The cams actuating the several valves are keyed on one and the same shaft. By shifting this shaft longitudinally, the cams controlling the admission are changed and they are caused to move 30 from the position for producing motion of the motor in one direction, into the position for producing the reverse motion. That arrangement has the disadvantage that the longitudinal shifting of the shaft can be effected only after the exhaust valves have 35 been opened, necessitating a loss of time and the provision of special mechanism.

Now the present invention has for its object to effect the desired reversal of the direction of the motor by means of a simple mechanism, easy to make and easy to operate with precision.

The invention consists substantially in providing two shafts, one shaft carrying the 45 cams that control the admission of the fuel and the admission of the compressed air for effecting the reversal of the direction of the motion of the motor, while the other shaft carries the cams that control the exhaust or 50 scavenging; the eccentric that controls the

reversing operation being carried by a fixed axle.

The accompanying drawings illustrate by way of example one construction of the improved mechanism, Figure 1 being an elevation, and Fig. 2 a plan thereof.

3 is the lever controlling the admission of the combustible mixture, and 4 is the lever controlling the admission of the compressed air. These two shafts are actuated by the 60 shaft 2. The lever 6 controlling the exhaust valve is actuated by the shaft 1. The rotary shaft 2 is also movable in the direction of its length and it carries cams 4^a and 4^b for controlling the admission of the compressed air, 65 and cams 3^a and 3^b for the admission of the fuel for both directions of motion of the motor. The shaft 1, which is fixed against axial movement, carries an ordinary cam 1^a that revolves loose between a tappet 1^b 75 placed in the desired position on the shaft to position the cam portion 1^c to open, and so retain the exhaust port, during the desired period, that is, when the rotation of shaft 1 is reversed, there is a certain amount 80 of lost motion between the shaft and cam 1^a until the tappet 1^b carries the cam with it and so positions portion 1^c thereof for the desired actuation of the exhaust port control means.

Upon the eccentric 5 that serves as a support for the levers 3 and 4, there is fixed a sector having three notches which correspond to the positions of starting the motor, 85 stopping the motor, and admission of the 90 compressed air.

Assuming that the motor is revolving in the forward direction the reversal of the direction of motion of the motor is effected as follows:—The operator places the sector of the eccentric 5 at the stopping notch. The levers 3 and 4 then allow free passage to the cams 3^a, 3^b, 4^a, and 4^b, keyed on the shaft 2 which latter is shifted, through forked lever 7 operating between collars 8 on the shaft, in the direction of its length, by the operator, until the cams 3^b and 4^b, for backward motion, come under the said levers. As the motor continues to revolve by the action of the flywheel, or the propeller in the case of a boat, the operator places the sector at the notch for admitting the compressed air. The compressed air entering the motor cylinder at from about 50 to 70 per cent. of the length of the stroke in front of the outer 100 105 110

dead center of the piston, exerts a braking action upon the motor and finally causes the motor to move in the opposite, *i. e.* the rearward direction. After a few revolutions, the operator places the sector at the running notch, and the motor is then worked in the usual way by means of fuel.

Claims—

1. An engine comprising in combination, a cylinder provided with fuel and fluid pressure valved inlets, a valved exhaust outlet, an adjustable eccentric shaft, a fuel valve control lever mounted on the said shaft, a fluid pressure valve control lever mounted on the said shaft, a rotatable and longitudinally adjustable cam shaft, a plurality of sets of cams on said shaft adapted to operate said fuel valve control lever and said fluid pressure valve control lever, for either forward or reverse movement of the engine shaft, when disposed in the path of said levers, means shifting said eccentric shaft whereby both of the said levers, the fluid pressure valve control lever, or neither of the levers are in the path of the said cams, a rotatable shaft provided with a cam, and a lever operative by the said cam for actuating said exhaust valve.
2. An engine comprising in combination, a cylinder provided with fuel and fluid pressure valved inlets, a valved exhaust outlet, an adjustable eccentric shaft, a fuel valve control lever mounted on said shaft, a fluid pressure valve control lever mounted on the said shaft, a rotatable and longitudinally adjustable cam shaft, a plurality of sets of cams on said shaft adapted to operate said fuel valve control lever and said fluid pressure valve control lever for either forward or reverse movement of the engine shaft, when disposed in the path of said levers, means for adjusting said cam shaft whereby the sets of cams may be located in operative relation to said levers to provide for either forward or reverse movement of the engine shaft, means shifting said eccentric shaft whereby both of the said levers, the fluid pressure valve control lever, or neither of the levers are in the path of the said cams, and means for operating said exhaust valve.
3. An engine comprising in combination, a cylinder provided with fuel and fluid pressure valved inlets, a valved exhaust outlet, an adjustable eccentric shaft, a fuel valve

control lever mounted on said shaft, a fluid pressure valve control lever mounted on the said shaft, a rotatable and longitudinally adjustable cam shaft, a plurality of sets of cams on said shaft adapted to operate said fuel valve control lever and said fluid pressure valve control lever for either forward or reverse movement of the engine shaft, when disposed in the path of said levers, means adjusting said cam shaft whereby the sets of cams may be located in operative relation to said levers to provide for either forward or reverse movement of the engine shaft, means shifting said eccentric shaft whereby both of the said levers, the fluid pressure valve control lever, or neither of the levers are in the path of the said cams, a rotatable shaft provided with a cam, and a lever operative by the said cam for actuating said exhaust valve.

4. An engine comprising in combination, a cylinder provided with fuel and fluid pressure valved inlets, a valved exhaust outlet, an adjustable eccentric shaft, a fuel valve control lever mounted on said shaft, a fluid pressure valve control lever mounted on the said shaft, a rotatable and longitudinally adjustable cam shaft, a plurality of sets of cams on said shaft adapted to operate said fuel valve control lever and said fluid pressure valve control lever for either forward or reverse movement of the engine shaft, when disposed in the path of said levers, means for adjusting said cam shaft whereby the sets of cams may be located in operative relation to said levers to provide for either forward or reverse movement of the engine shaft, means shifting said eccentric shaft whereby both of the said levers, the fluid pressure valve control lever, or neither of the levers are in the path of the said cams, and means for operating said exhaust valve.

In testimony that I claim the foregoing as my invention, I have signed my name in presence of two subscribing witnesses.

GUSTAVE CARELS.
